UNITED STATES PATENT OFFICE.

MAYHEW E. NOYES, OF CLEVELAND, OHIO, ASSIGNOR TO THE OHIO GEAR GRINDING COMPANY, A CORPORATION OF OHIO.

GEAR-GRINDING MACHINE.

1,191,093.

Specification of Letters Patent. Patented July 11, 1916.

Application filed December 1, 1913. Serial No. 804,092.

To all whom it may concern:

Be it known that I, MAYHEW E. NOYES, a citizen of the United States, residing at Cleveland, county of Cuyahoga, State of Ohio, have invented a certain new and useful Improvement in Gear-Grinding Machines, and declare the following to be a full, clear, and exact description of the same, such as will enable others skilled in the art to which it pertains to make and use the same, reference being had to the accompanying drawings, which form a part of this specification.

This invention relates to gear grinding machines and has for its object a simple and efficient device for successively grinding the teeth of a gear blank to conform perfectly to the contour line upon which they have been laid out and cast or cut.

20 A further object of the invention resides in the means employed whereby each tooth of the blank may be ground exactly to the same size and form, to accomplish which a templet, having the face contour of a finished gear tooth, is utilized to determine the path of movement of the tooth of the blank in its engagement with the grinding wheel.

25 A further object resides in the means whereby the engagement of the templet with a finder rolls the gear during the time the tooth is in engagement with the grinding wheel, and another object resides in the means utilized in indexing the gear wheel whereby the teeth thereof are operated upon 30 in succession.

35 Another object resides in the means whereby gears of various diameters may be operated upon with equal facility.

These and further objects and novel features of construction are hereinafter more fully described and claimed and shown in the accompanying drawings in which—

Figure 1 is a side elevation of a grinding machine embodying my invention. Fig. 2 is an end elevation thereof. Fig. 3 is a section on line *y*—*y* of Fig. 1, showing the mechanism for operating the slide carrying the gear blank to be operated upon and a portion of the indexing mechanism. Fig. 4 is a section on line *B*—*B* of Fig. 3. Fig. 5 is a section taken on line *a*—*a* of Fig. 2. Fig. 6 is a detail of the mechanism controlled by the movement of the slide to reverse its direction of movement. Fig. 7 is 55 an enlarged vertical section taken on line

A—A of Fig. 1 showing the work holding shaft and mechanism through the medium of which it is controlled. Fig. 8 is an enlarged view showing the path of the gear tooth in its engagement with the grinding wheel. Fig. 9 is a plan view of the means for adjusting the grinding wheel shaft longitudinally. Fig. 10 is a detail in perspective of part of the clutch operating mechanism.

60 In the drawings 1 indicates the hollow base or bed of the machine upon which is mounted a slide member 2 riding in a way 3 on the base. At the forward end of the base is secured the vertically extending head 4. On the head 4 is supported a block 5 riding in ways 6, 6 provided therefor, adjustable vertically on the head by means of the screw 7 fixed thereto, which passes through the adjusting nut 8 held in fixed 65 position on the head by the bracket 9. The nut 8 is provided with a hand-wheel 10 by means of which it may be easily rotated. The block 5, as is hereinafter more fully described, supports the shaft 11, on the end 70 of which is mounted the grinding wheel 12 preferably provided with a casing 13. On the shaft 11 is a belt wheel 14 driven by a belt 15 from the shaft 16 which in turn is driven by the belt 17 from any convenient 75 source of power. The shaft 16 is carried at the upper end of a bracket 18 pivotally supported at 19 to the vertical head 4. Pivoted to the bracket near the upper end is 80 a rod 20 which is also pivotally secured at 21 to the block 5. This arrangement enables the shaft 16 to be maintained in substantially its proper relation with the shaft 11 under alteration of the position of the shaft 11 incident to the shifting of the block 85 90 95 5 on the head 4.

The slide member 2 is provided with suitable bearings in which is supported the work supporting shaft 22 upon the outer end of which is supported the toothed blank 23 in 100 vertical alinement with the grinding wheel shaft. The gear blank is brought to and from the grinding wheel by reason of the reciprocation of the slide 2 which is produced by mechanism hereinafter described.

105 The work holding shaft 22 is rotatably mounted in the bearings provided, and is subject to a rotary movement imparted thereto in two ways, namely; the movement on its axis by means of which the tooth is 110

made to engage the face of the grinding wheel on the desired contour line both in approaching and receding from the grinding wheel caused by the reciprocation of the slide, and also the movement on its axis during the time the blank is out of engagement with the grinding wheel whereby said blank is indexed and a succeeding tooth brought to position to be operated upon during a succeeding forward movement of the slide.

The indexing means, which is hereinafter more fully described in detail, includes a worm shaft 23^a and worm 24 thereon, which is continuously in engagement with the work wheel 25 rotatably mounted on the work holding shaft. The worm wheel 25 carries a clutch member 26 upon one side thereof which may be of any approved form, but is shown as a cone friction clutch engaged by the cone 27 splined on the shaft 22. Whenever the clutch 27 is thrown into engagement with the member 26 during operation of the worm shaft 23^a, the shaft 22 is rotated on its axis.

The movement of the shaft 22, by which the path of the gear tooth in its engagement with the grinding wheel is determined, is produced through the medium of a templet 28 having the same contour as the gear tooth and which engages a finder 29 adjustably secured to the vertical head 4, by means of a bolt 30, as may be more clearly seen in Fig. 7.

The templet 28 is held on the arm 31 of the carrying member 32 by a bolt 33, the head of which rides in a T shaped slot 34 in the arm 31. The radial distance of the templet from the center of the shaft 22 may thus be set to agree exactly with the radius of the pitch circle of the gear blank. The templet carrier 32 is provided with a clutch member 35 adapted to be engaged by a corresponding member 36 which is preferably formed integrally with the clutch member 27 heretofore described.

The templet 28 is held in engagement with the finder 29 by means of a spring 37 attached to the lower end of the templet member 32 and to a convenient part of the frame-work as shown in Fig. 5, and as the slide member 2 moves forward toward the grinding wheel, and with the clutch 36 in engagement with the companion 35, the shaft 22 is made to turn in a manner determined by the contour of the templet. The tooth of the blank, therefore, has the identical path of movement in engagement with the grinding wheel as that of the templet in engaging the finder. As hereinafter shown, the clutch member 36 remains in engagement with the companion member 35 during that portion of the forward and backward movement of the slide in which the tooth of the blank engages the grinding wheel and the entire face of the tooth is thus twice sub-

jected to the grinding action of the grinding wheel. Therefore, whatever form the tooth of the blank may have, it will be ground on desired line by the use of a templet of the same form. I am aware of other devices for this purpose in which a work holding shaft is made to rotate, as the gear tooth is brought into engagement with the grinding wheel, by means of a tape, but such device rotates the work holding shaft at a predetermined uniform rate, while with the device here disclosed the work holding shaft may turn quite rapidly during the initial engagement of the tooth with the grinding wheel, and during the latter part of the engagement therewith the blank may not be perceptibly rotated, thus making a flat and straight surface below the pitch line of the tooth, or it may be curved and made to engage the wheel on a curved line by more rapidly turning the shaft through the use of a templet of the proper form.

The movement of the tooth to and from the grinding wheel is indicated somewhat diagrammatically in Fig. 8, showing the tooth of a gear wheel whose center is on the dotted line $z-z$, indicating the path on which said center moves by reason of the movement of the slide. In coming into engagement with the grinding wheel, the point of the tooth is the first to engage the wheel as shown at a , the next succeeding position is shown by the dotted lines b , and a succeeding and final position is shown by the dotted lines c , the center of the gear moving from a^1 to b^1 , and c^1 , and then retreating to a slight distance beyond a^1 , as d^1 ; at which point the work shaft is rotated by the worm wheel 24 to the right from the position shown in Fig. 8 to bring the next succeeding tooth to position to engage the grinding wheel on the next forward movement of the work-shaft and slide.

The grinding wheel shaft 11, as shown more clearly in Figs. 1, 2 and 9 is supported in bearings in a head 38 carried on a block 39 by means of the undercut way portion 40. A screw 41 is in threaded engagement with the block 39 and provided with a circumferentially grooved head 42 which is engaged by a bracket 43 secured to the head 38. By turning the screw, the head 38 is moved longitudinally of the block 39 which moves the shaft 11 longitudinally and the grinding wheel thus set in proper position for engagement by the gear tooth and enables adjustment to be made as the face of the grinding wheel wears. The block 39 is secured to the block 5 by bolts 44, and the block 5 is provided with a central raised portion 45 fitting a recess provided in the block 39. The bolts 44 pass through slots provided in the block 39, whereby said block may be turned on the block 5 and the angular position of the grinding wheel 12 relative to the

work altered. In some instances, especially with small gear blanks, it is preferable to set the grinding wheel at an angle to the vertical in order that the tooth may properly engage the face of the wheel and the succeeding tooth kept out of contact therewith as the slide reciprocates.

The shield 13, inclosing the grinding wheel, is provided with a slotted guide-way 10 46¹ on the upper side thereof adapted to hold a diamond pointed tool for facing the grinding wheel and maintaining a flat grinding surface.

The machine is operated by means of a drive wheel 46 loosely mounted on the shaft 47 and provided with a clutch operated by the member 48 splined on the shaft and provided with a hand-lever 49^a through the medium of which the machine may be thrown 20 into and out of operation. On the shaft 47 is a gear wheel 49 meshing with a gear 50 which, as shown more clearly in Figs. 5 and 6 is mounted on a tubular hub 51 to which is attached one member 52 of a toothed 25 clutch. The gear 50, hub 51 and clutch member 52 support one end of the main operating shaft 53 and are rotatable relative thereto, the shaft 53 being rotatable only at such time as the clutch member 54 splined 30 on the shaft is brought into engagement with the clutch member 52. The clutch member 54 is thrown into and out of engagement with the companion member 52 through operation of the forked arm 55, 35 which is produced through the rocking of the cross-shaft 56.

As shown more clearly in Fig. 4, the shaft 56 extends entirely across the bed of the machine, and projects through on the side 40 thereof upon which end is mounted a forked arm 57, operatively engaging a two-faced clutch member 58 on a shaft 59, which is mounted in brackets attached to the side of the bed and receives its motion through a 45 gear 60, continuously in mesh with the gear 49 on the drive-shaft 47.

The cross-shaft 56 is rocked and the clutches 52 and 54 operated through movement of the slide member 2, which swings 50 the lever 61 to and fro upon its pivot by reason of the engagement of the adjustable stops 62 and 63 therewith, as may be clearly inferred from Fig. 1. The lever 61 is pivoted to the frame-work at 64, and in pivotal 55 connection with the lever 61 is a rock-arm 65 attached to a rock-shaft 66, carried in a bearing in the bed of the machine. As may be seen more clearly in Figs. 3 and 6, a forked arm 67 depends from the inner end 60 of the rock-shaft 56 engaging in a groove in a slide 68 loosely mounted on the shaft 69, and movable longitudinally thereof. The shaft is supported in brackets 70 and 71 secured to the side frame of the bed and at the outer end is pivotally attached to a

link 72, which in turn, is pivoted to a rock-arm 73 pinned to the shaft 56. On each side of the slide member 68 and spaced therefrom are blocks 74 and 75 pinned to the shaft 69 and, between the slide member and each block respectively are interposed the coiled springs 76 and 77. Also pivotally mounted on each bracket 70 and 71 are the pawls 78 and 79 provided with a notch 80, in both instances, behind which the block 74 75 or 75 may engage and hold the shaft 69 from longitudinal movement until the pawl is disengaged. As the slide member 2 moves backward away from the grinding wheel the lever 61 is swung on its pivot rocking the shaft 66 and consequently moving the block 68 on the shaft 69 to the right of the position shown in Fig. 6. This movement first compresses the spring 76 as the block 74 is held by the pawl 79 and, consequently, the shaft 69 is held from movement. The forked arm 67 is provided with trip arms 81 and 82 upon each side thereof, and as the movement of the forked arm 67 to the right continues, the trip arm 82 lifts the pawl 79 90 which releases the block 74 allowing the spring 76 to expand and move the block and the shaft to the right. The spring 76 being under compression at this time causes a sudden movement of the shaft longitudinally 95 in its bearings, and as the shaft is connected to the rock arm 73 the shaft 56 is rocked.

As may be seen more clearly in Fig. 10, a rock-arm 83 is pinned to the shaft 56 the upper end of which normally engages the 100 notched pawl 84 pivotally supported on the forked arm 55. The pawl is normally held in engagement with the end of the arm by means of a coiled spring 85 extending between the end thereof and the lug 86 carried by the rock arm. By this arrangement the rocking of the shaft 56 toward the right of Fig. 6 throws the clutch 54 into engagement with the companion 52 which is continuously rotated, as before stated. This movement of the clutch and forked lever 55, 110 which is loose on the shaft 56, places the spring 87 under tension.

Integrally formed with or secured to the sliding clutch member 54 is a disk 88 having a lug 89 on the periphery thereof which is adapted to engage the end 90 of the pawl 84 raising it from engagement with the rock arm 83 and releasing the forked arm 55 to the influence of the spring 87 which disengages the clutch member 54 with its companion 52. The main operating shaft 53 therefore, makes only one complete revolution at each actuation. As before stated, the shaft 56 also has a forked arm 57 attached thereto engaging the two-faced clutch member 58 on the shaft 59 shown more clearly in Fig. 3. When the shaft 56 is rocked through the described longitudinal movement of the shaft 69 and the clutch 54 130

thrown into engagement with its companion, the clutch member 58 is also moved longitudinally on its shaft, but does not engage one companion member 90^a thereof, for the reason that the member 58 must necessarily move a greater distance than the clutch 54. Therefore, the first movement of the rock-shaft 56 caused by the compression of the spring 76 causes the clutch 54 to engage the clutch 52 and, when said clutch 54 is released by the means heretofore described, the shaft 56 will be rocked farther to the right, due to the fact that the spring 76 is still under considerable compression, and throw the clutch member 58 into engagement with the clutch member 90^a and this engagement of the clutch members 58 and 90^a causes a reversal in the direction of movement of the slide member 2 which, prior to this engagement of the clutch was moving backward away from the grinding wheel.

The slide is reciprocated by the following described mechanism—The clutches 90^a and 91 are loose on the shaft 59 and are formed on or connected with the hubs of the bevel pinions 92 and 93 respectively, which are continuously in mesh with the bevel wheel 94 on the shaft 95 carried in a bearing provided in the bed. Thus, while the shaft 59 is continuously rotated through the medium of the gear 60, the gears 92 and 93 are not rotated except as the clutch thereon is engaged by the two-faced clutch member 58 splined on the shaft 59, the engagement of the clutch 58 with the clutch 91 rotating the bevel wheel 94 in one direction, while engagement of the opposite face of the clutch 58 with the clutch 90^a rotates the bevel gear 96 in the opposite direction. Loosely mounted on the inner end of the shaft 95 is a gear 98 meshing with an idler 97 which in turn meshes with a spur gear 98 on a stub shaft 99 secured in the frame of the bed. The gear 98 meshes with a rack 100 on the lower side of the slide member and rotation of the gear 98 in one direction moves the slide forward and reversal of its direction of rotation moves the slide backward which is accomplished by the operation of the clutch 58. Splined on the inner end of the shaft 95 is a clutch member 101 normally in engagement with its companion clutch on the loosely mounted gear 96.

In order that the slide may be operated by hand and the relative position of the grinding wheel and gear blank be accurately determined, the clutch 101 is operated by the lever 102 pivotally supported on the end of the stub shaft 99 and provided with a forked end engaging in a groove in a sliding member 103 on a shaft 104 which extends across the machine as shown in Figs. 1, 3 and 5. The shaft 104 is hollow in which is positioned a shifting rod 105 terminating upon

the outer face of the machine in a knob 106. The shaft 104 is slotted at 107 in which rides a pin 108 secured to the operating rod 105 and the sliding member 103. By pulling the operating rod outward, the clutch 101 is disengaged from its companion on the gear 96 which is loose on the shaft and the gear 98 may then be actuated through the medium of the gear 109 on the hand operated shaft 94 meshing with the gear 96. The shaft 104 may be operated through the medium of the wheel 110, and this operation by hand does not interfere with the automatic operation of other parts of the mechanism produced through the driving mechanism heretofore described.

The indexing shaft 23^a is operated in the following manner: Supported in bearings provided in the bed, and lying parallel to the main operating shaft 53, is a shaft 111 on which is mounted a spur gear 112 meshing with a gear 113 on the main operating shaft 53. The gear 112 is carried on a sleeve which is rotatable relative to the shaft and carried upon one end thereof is one member 114 of a friction clutch whose companion 115 is keyed to the shaft. The clutch members are continuously in frictional engagement and the member 115 is normally held from rotation by the rock lever 116 having an end engaging in a notch 117 in the member, as is shown more clearly in Fig. 7. The lever 116 is held in contact with the clutch member by a spring 118 and is secured to the rock-shaft 119 supported in bearings on the side of the bed. Near one end the shaft 119 is provided with a trip arm 120 which is engaged once every revolution of the shaft 53, by a roller 121 mounted on the disk 122, which is secured to the main operating shaft 53. The parts are so relatively arranged that, as the shaft 53 starts to revolve through operation of the mechanism heretofore described, the trip arm 120 is actuated which withdraws the end of the lever 116 from the notch 117, and releases the clutch member 115 to the influence of its companion 114 thereby rotating the shaft 111. It is to be noted that the gear 113 is considerably larger in diameter than the gear 112 whereby a single rotation of the gear 113 turns the gear 112 more than one revolution, but through the automatic operation of the lever 116, which automatically drops into the notch provided in the clutch member 115, only a single revolution of the shaft 111 is possible at a single actuation by the main shaft 53, but such revolution is made much more quickly than the single revolution of said main shaft to enable the operation of indexing to be performed within the necessary time limit.

On the outer end of the shaft 111 is a spur gear 123 which meshes with an idler gear 124, removably mounted in the bracket

125, which is pivoted to the end of the framework. The gear 124 has the same number of teeth as the blank to be operated upon by the grinding wheel, and the relation of parts is such that one revolution of the shaft 111 turns the work-shaft to index the gear blank, and, as gear blanks of different sizes are to be operated upon, a gear 124 of the same size and number of teeth as the gear blank, is necessarily utilized to properly index the blank. As gears of various diameters are to be utilized to perform the function of the idler gear 124, it is mounted in the pivoted bracket 125 so as to swing toward or from the gear 123 and the gear 126 on the indexing or worm-shaft 23^a to accommodate the change in size. The lever 116 is tipped and the indexing mechanism actuated at a time when the slide 2 has withdrawn the blank from engagement with the grinding wheel.

The cone clutch 27, utilized to alternately connect the worm-wheel 25 and the templet carrier 32 with the work-shaft 22, is operated through the medium of a forked-lever 127, pivoted at 128 to brackets carried by the slide member 2, the lower end of which extends downward into the base of the machine terminating in the forked arms 129 and 130, disposed upon opposite sides of the cam disk 131 splined on the shaft 53. The cam disk is movable longitudinally of the shaft by reason of its being interposed between brackets 132 and 133 attached to the slide and is, therefore, carried in fixed relation with the forked arms 129 and 130, and the slide 2. The cam disk is provided with cam members 134 and 135 upon opposite faces thereof as may be seen in Fig. 3, and contact of the cam 134 with the fork end 130 throws the clutch 36 into engagement with its companion 35, while the engagement of the cam 135 with the fork end 129 throws the clutch 27 into engagement with its companion 26 on the worm wheel. These cams are so arranged and timed to operate that, as the blank is withdrawn from engagement with the grinding wheel which is near the finish of the backward stroke of the slide 2, the worm wheel is clutched to the shaft and the blank indexed, and the clutch then disengaged from the worm wheel and thrown into engagement with the templet carrying member, both of these acts being performed during a single revolution of the main operating shaft 53. With the templet carrying member clutched to the work-shaft the slide then moves forward presenting the tooth to the grinding wheel and withdrawing it therefrom in a path whose contour is that of a finished gear tooth, and as the slide again approaches its backward position the blank is again indexed and the operation repeated, the actuating mechanism being automatically oper-

ated and controlled in the manner heretofore described.

While I have shown and described a particular form and arrangement of the actuating mechanism by which the work-shaft 70 may be brought into operation in the desired manner and through the mechanism of which the slide is reciprocated, it is possible to accomplish the same result by mechanism of other forms and arrangement. I, therefore, do not limit myself to the exact form and arrangement of such actuating mechanism but

What I do claim and desire to secure by Letters Patent of the United States is—

1. In mechanism of the kind described, a grinding device for operating on the face of a gear tooth, a reciprocable holder for carrying a toothed blank, means for reciprocating the work holder to bring a tooth of the blank into and out of engagement with the grinding device, and a templet carried by the work holder through the medium of which the path traversed by the tooth during its engagement with the grinding device is determined.

2. In mechanism of the kind described, a grinding device for operating on the face of a gear tooth, a holder for carrying a toothed blank, means for moving the holder to bring a tooth of the blank into and out of engagement with the grinding device, and a templet of the same size and contour as a finished gear tooth through the medium of which the tooth of the blank engages the driving device in a path having the contour of a finished gear tooth.

3. In mechanism of the kind described, a work-holding shaft, a frame having bearings for the shaft and being movable transversely of the longitudinal axis thereof, a templet having the contour of a finished gear tooth, grinding means for operating upon a gear tooth, and automatic mechanism for reciprocating the said frame to bring the shaft 105 toward and from the grinding means, the templet determining the path of movement of the tooth in engaging the grinding means.

4. In mechanism of the kind described, an axially fixed work-holding member, a templet having the same size and contour as a finished gear tooth carried by said member, grinding means for operating upon a gear tooth, automatic mechanism for bringing the work-holding member toward and from the grinding means, a finder with which the templet engages, means whereby the engagement of the templet with the finder determines the path of movement of the tooth in engaging the grinding means, and indexing means for said gear adapted to operate the work-holding member at a time when the gear tooth is out of engagement with the grinding means.

5. In mechanism of the kind described, a

rotatable grinding wheel, a holder for toothed blanks, mechanism for reciprocating the holder to bring a tooth of the blank into and out of engagement with the grinder, and 5 a templet having the contour of a finished tooth through the medium of which the path of movement of the tooth of the blank in engaging the grinding wheel is determined.

6. In mechanism of the kind described, a 10 grinding wheel, a shaft for toothed blanks reciprocable transversely of its longitudinal axis to bring the blanks to and from the grinding wheel, and a templet radially adjustable relative to the shaft and having a 15 contour of a finished gear tooth through the medium of which the shaft is turned and a tooth of the blank made to engage the grinding wheel in a path having the contour of a finished gear tooth as the shaft moves both 20 to and from the grinding wheel.

7. In mechanism of the kind described, a 25 rotatable grinding wheel having a practically flat face held in angularly fixed relation to the blank to be operated upon, a holder for toothed blanks having a reciprocating movement, and means for imparting a varied rotary movement to the holder whereby a tooth of the blank engages the grinding wheel in a path whose contour is that of a 30 finished gear tooth.

8. In mechanism of the kind described, a 35 rotatable grinding wheel angularly adjustable relative to the blank to be operated upon and also adjustable to accommodate blanks of various pitch diameters, a holder for toothed blanks, means for moving the holder to and from the grinding wheel, and a templet through the medium of which a tooth of the blank engages a grinding wheel 40 on a path having the contour of a finished gear tooth during both the forward and backward movement of the holder.

9. In mechanism of the kind described, a 45 rotatable grinding wheel, means for adjusting the angle of the wheel relative to the blank to be operated upon, means for adjusting the wheel to accommodate toothed blanks of various pitch diameters, means for adjusting the wheel to take up wear caused by the grinding operation, a holder for toothed blanks, means for moving the holder to and from the grinding wheel, and means for imparting a movement to the holder during its 50 to and fro movement whereby a tooth of the blank engages the grinding wheel in a path having the contour of a finished gear tooth.

10. In mechanism of the kind described, a 55 continuously rotatable grinding wheel adjustable to accommodate toothed blanks of various pitch diameters, a holder for said blanks, automatic means for moving the holder to and from the grinding wheel, and a templet through the medium of which a tooth of the blank is made to engage the 60 grinding wheel on a path having the con-

tour of a finished gear tooth, said templet being adjustable to correspond with the adjustment of the grinding wheel.

11. In mechanism of the kind described, a 65 continuously rotatable grinding wheel, a holder for toothed blanks, automatically operating means for moving the holder to and from the grinding wheel, manually operable means for moving the holder to and from the grinding wheel, means for disengaging the automatically operating means, and a templet through the medium of which a tooth of the blank is made to engage the grinding wheel in a path having the contour of a finished gear tooth. 70 80

12. In mechanism of the kind described, the combination of a rotatable grinder, a holder for toothed blanks, means for moving the holder toward and from the grinder, a templet carrying member mounted on said 85 holder, a templet carried thereby, a finder for said templet, the engagement of the templet with the finder operating to determine the path of movement of a tooth of the blank in engaging the grinder, mechanism 90 for rotating the holder to index the blank operating at a time when the tooth is out of engagement with the grinder, and means for alternately connecting the templet carrying device and the indexing mechanism with the 95 holder.

13. In mechanism of the kind described, a 100 grinding wheel for operating on the face of a gear tooth, a rotatable work holding shaft movable to bring a tooth of the gear blank into and out of engagement with the grinding wheel, a templet of the same size and having the same contour as the face of a finished gear tooth carried by the work holding shaft, said templet being adjustable 105 from the shaft center equal to the radius of the pitch circle of the gear blank to be operated upon, said grinding wheel being adjustable in position to accommodate gears 110 of various pitch diameters, a fixedly positioned finder for said templet, automatically operated means through the medium of which the templet may turn the work holding shaft during the time a gear tooth is 115 in engagement with the grinding wheel and determine its path of movement relative thereto, and alternately operatively connect the indexing means to the shaft at a time when the tooth is out of engagement with 120 the grinding wheel.

14. In mechanism of the kind described, a 125 base member having a vertically extending head portion, a shaft support vertically adjustable on said head, a shaft rotatably mounted in said support, a grinding wheel carried by said shaft, a slide movable horizontally on said base member, a work holding shaft carried by the slide, a templet 130 supporting member loosely mounted on the

work holding shaft, a templet carried by said member of the same size and having the same contour as a finished gear tooth, said templet being adjustable on its support 5 whereby it may be set a radial distance from the shaft center equal to the radius of the pitch circle of the gear blank to be operated upon, a finder for said templet secured to the vertically extending head 10 portion, automatically operated indexing means, a gear loosely mounted on the work holding shaft operatively connected with the indexing means and forming a part thereof, and automatic means for securing 15 the templet carrying member to the work holding shaft during the time the gear tooth is in engagement with the grinding wheel and thereby determine its path of movement relative thereto, and to alternately release said templet carrying member and secure the loosely mounted gear to the work holding shaft to turn said shaft and index 20 the gear blank at a time when the blank is out of engagement with the grinding wheel. 25 15. In mechanism of the kind described, a continuously rotatable grinding wheel, an axially fixed work holding member movable toward and from the grinding wheel, indexing means through the medium of which 30 the work holding member may be turned to index the blank, a templet member supported by the work holding member, a templet carried by said member, means adapted to alternately operatively connect 35 the indexing mechanism and the templet carrying member with the work holding member, a finder for the templet, a driving means, automatic means connected with the driving means for moving the work holding member to and from the grinding 40 wheel, the templet and finder providing a means whereby a tooth of the blank moves through a path having the contour of a finished gear tooth in its engagement with the grinding wheel, a main operating shaft, 45 means operated by movement of the work holding member to intermittently connect said main shaft with the driving means, means actuated by said main shaft for operating the means for alternately connecting 50 the indexing means and the templet member with the work-shaft, an indexing shaft movable to and fro with the work holding member, a gear splined thereon, a drive shaft actuatable by the main operating 55 shaft, means limiting said drive shaft to one complete revolution at each actuation, a gear on said drive shaft in alinement with the gear on the movable indexing shaft, and a removable indexing gear interposed between 60 said gear on the drive shaft and the gear on the indexing shaft through the medium of which the work-holding shaft is revolved to index the blank, and a pivotally mounted bracket for carrying said gear whereby indexing gears of various pitch diameters may be utilized. 65

In testimony whereof, I sign this specification in the presence of two witnesses.

MAYHEW E. NOYES.
